UNITED STATES PATENT OFFICE.

HAROLD M. GRAHAM, OF PITTSBURGH, PENNSYLVANIA, ASSIGNOR TO ELLIOTT COMPANY, OF PITTSBURGH, PENNSYLVANIA, A CORPORATION OF PENNSYLVANIA.

SURFACE CONDENSER.

1,409,944.

Specification of Letters Patent. Patented Mar. 21, 1922.

Application filed June 9, 1920. Serial No. 387,774.

To all whom it may concern:

Be it known that I, HAROLD M. GRAHAM, a citizen of Canada, residing at Pittsburgh, Allegheny County, Pennsylvania, have invented a new and useful Improvement in Surface Condensers, of which the following is a full, clear, and exact description, reference being had to the accompanying drawings, forming part of this specification, in 10 which:

Figure 1 is a view, partly in side elevation and partly in vertical section showing a portion of the surface condenser embodying my invention, and

15 Figure 2 is a view partly in end elevation and partly in vertical section of the condenser.

20 My invention has relation to surface condensers and is designed to provide a construction and arrangement of the surface condenser and its circulating and condensate pumps such that the work of disassembling the pumps for inspection and repairs is greatly facilitated.

25 Heretofore, surface condensers have been made with a condenser shell, mounted directly over the pumps, in such a manner that the units have been made very compact; but there has been great difficulty in disassembling the pump structures owing to the fact that many of the parts are inaccessible. The result has been that the labor of demounting them in case they had to be inspected, or in case of trouble in their operation, has 35 been such to impair the success of the apparatus.

The nature of my invention will be best understood by reference to the accompanying drawings which will now be described, 40 it being premised, however, that various changes may be made in the details of construction, arrangement and combination of the parts, without departing from the spirit and scope of my invention as defined in the 45 appended claims.

In these drawings, the numeral 2 designates the shell of a surface condenser which is partially supported on one or more feet 3, and the pump end of which is supported on 50 the circulating pump 4. This pump is, in turn, supported on removable blocks 5 which are inserted between the pump and the main foundation in such a manner that they may be readily removed to permit the pumps to

be dropped to such an extent that they can 55 be freed from the joints at 6 where they meet the condenser, and thus facilitate their removal. 7 designates the condensate pump and 8 the hot well. This hot well is suspended from the condenser, and partially 60 supports the casing of the condensate pump, said casing being further supported by the rigid hollow connecting member 7^a connected to the casing of the circulating pump.

It will be noted by reference to Figure 2 65 that the longitudinal center line of the pumps is offset (to the right, looking at Figure 2) with respect to the center line of the condenser. Each of the pump casings is split vertically in a longitudinal vertical 70 plane which coincides with the center of the pump shaft 9, this plane being preferably just to one side of the connections between the condenser and the pumps. The connecting member 7^a does not entirely enclose 75 the shaft, but has an open side which permits removal of the pump shaft and also provides for access to the stuffing boxes for the shaft. This member is preferably also formed with a detachable transverse joint 80 at 7^b. Each pump casing has an endwise extending bracket 7^c which supports a bearing 7^d for the shaft 9. These bearings are of the usual split character; and the boxes 7^e in which they are seated have the usual 85 removable cover portions. The shaft 9 is shown as being common to both pumps, although this is not essential to my invention.

By reason of the described construction, it will be readily seen that the removable sections of the pump casings (these sections being shown removed in Figure 1 and one of them being shown at 10 in Figure 2) can be quickly and easily taken off and the shaft and pump rotors removed laterally in the 95 space underneath the overhanging portion of the surface condenser shell. In effecting this removal, the covers of the boxes 7^e are removed. The upper halves of the sectional bearings 7^d are then removed and the lower 100 halves turned on the shaft journals to a position above said journals where they can also be removed. The shaft is thus entirely freed and may be laterally removed, together with its stuffing boxes and the rotor elements 105 carried thereby. It is, therefore, possible to bring the foundation walls of the turbine which the condenser serves, up to approxi-

mately the limitation of the condenser shell. In other words, I provide all the space which is required for disassembling the pumps within the ordinary foundation construction. In the constructions used heretofore, with which I am familiar, the pumps have been split in planes transverse to the axis. This makes it necessary in removing the pump shaft and rotors to serially unsplit 5 the various parts and remove one or more runners of the shaft before the shaft can be pulled out endwise. The construction herein shown and described makes it possible to remove the shaft without removing 10 any of the runners, and, as above described, the space underneath the overhanging portion of the condenser shell is amply sufficient to permit this to be readily done.

I preferably extend the pump shaft 9 20 at both ends so that a driving pulley or other driving means may be secured to either end portion, as may be desired.

I also preferably provide the circulating pump with an inlet connection 11 at the 25 bottom and also with a similar inlet connection 12 at the back, whereby water may be introduced into said pump either at the bottom or the side, the opening not used being suitably closed.

30 I claim:

1. The combination of a surface condenser and its condensate and circulating pumps, said condenser being mounted directly above said pumps, and the latter having their 35 casings split in longitudinal vertical planes, substantially as described.

2. The combination of a surface condenser and its condensate and circulating pumps, said condenser being mounted directly above 40 said pumps, the latter having their casings split in longitudinal vertical planes, the pumps being offset laterally with respect to the central vertical plane of the condenser, substantially as described.

45 3. A surface condenser and a circulating pump upon which the condenser is supported, said pump having its casing split in a longitudinal vertical plane, and the casing being offset to one side of the central vertical plane of the condenser, substantially as described.

50 4. The combination with a surface condenser, of circulating and condensate pumps, the condenser being supported directly above said pumps and upon the circulating pump, and said pumps having their casings split in longitudinal vertical planes, substantially as described.

55 5. The combination with a surface condenser, of circulating and condensate pumps, the condenser being supported directly above said pumps and upon the circulating pump, said pumps having their casings split in longitudinal vertical planes, and a 60 common shaft for said pumps, said shaft

being removable laterally from its bearings when the removable pump casing sections are removed, substantially as described.

6. The combination with a surface condenser, of circulating and condensate pumps, 70 said pumps having vertically split casings, and the condenser shell and condenser being supported on the circulating pump and overhanging the removable sections of the pump casings, substantially as described. 75

7. The combination with a surface condenser, of circulating and condensate pumps, said pumps having vertically split casings, and the condenser shell and condenser being supported on the circulating pump and 80 overhanging the removable sections of the pump casings, the circulating pump having openings whereby water may be introduced either at the bottom or at the side of said pump, substantially as described. 85

8. The combination with a surface condenser, of a circulating pump upon which the condenser is supported, said pump having circulating openings for introducing water at the bottom and side thereof, substantially as described. 90

9. The combination with a surface condenser, of circulating and condensate pumps, the condenser being supported directly above said pumps and the pumps being offset to 95 one side of the center line of the condenser, substantially as described.

10. The combination with a surface condenser, of circulating and condensate pumps, the condenser being supported directly above 100 said pumps and the pumps being offset to one side of the center line of the condenser, said pumps having their casing split in longitudinal vertical planes and having a common shaft arranged to be driven from 105 either end portion thereof, substantially as described.

11. The combination of a surface condenser, a circulating pump over and upon which the condenser is mounted, said pump 110 having its casing split in a longitudinal vertical plane, and a condensate pump in line with the circulating pump, substantially as described.

115 12. The combination of a surface condenser, circulating and condensate pumps over which the condenser is directly mounted, said pumps having their casings split in longitudinal vertical planes, and being offset with respect to the longitudinal 120 vertical center of the condenser, and a common driving shaft for said pumps, substantially as described.

125 13. The combination of a condenser, a circulating pump and a condensate pump, the condenser being supported directly over said pumps and upon the circulating pump, detachable connections between the pumps and the condenser shell, and means whereby the pumps may be dropped away from 130

- the condenser shell when said connections are detached, substantially as described.
14. The combination with a condenser, of a circulating pump therefor, a condensate pump, and means for rigidly connecting the casings of said pumps, said means having an open portion and the pump casings being split in longitudinal vertical planes, substantially as described.
15. The combination with a condenser, of a circulating pump therefor, a condensate pump, said pumps being placed under the condenser and having their casings split in longitudinal vertical planes, and means rigidly connecting the casings of said pumps, said means having an open side portion, substantially as described.
16. The combination with a condenser, of a circulating pump therefor, a condensate pump, said pumps being placed under the condenser and having their casings split in longitudinal vertical planes, and means rigidly connecting the casings of said pumps, said means having a laterally open portion, and said pumps having a common shaft removable laterally from the pumps upon removal of portions of the split casings, substantially as described.
17. In condenser apparatus, the combination of a condensate pump and a circulating pump, said pumps having their casings split in longitudinal vertical planes, and a member rigidly connecting said casings and having a laterally open portion, substantially as described.
18. In condenser apparatus, the combination of a condensate pump and a circulating pump, said pumps being placed side by side with longitudinally aligned shaft bearings and having their casings split in the same longitudinal vertical plane, a hollow member rigidly connecting the casings of the two pumps, and a shaft common to the two pumps and extending through the connecting member, substantially as described.
19. In condenser apparatus, the combination of a condensate pump and a circu-
- lating pump, said pumps being placed side by side with longitudinally aligned shaft bearings and having their casings split in the same longitudinal vertical plane, a hollow member rigidly connecting the casings of the two pumps, and a shaft common to the two pumps and extending through the connecting member, each of said casings also supporting outer bearings for said shaft, substantially as described.
20. In condensing apparatus, two centrifugal pumps having aligned stuffing boxes and shaft bearings and having their casings split in vertical longitudinal planes, together with means for rigidly connecting said casings and which permits access to said stuffing boxes, a common shaft for said pumps, and means rigidly connected to said casings and carrying bearings for said shaft, substantially as described.
21. The combination with a surface condenser, of a circulating pump over and upon which the condenser is supported, a condensate pump in line with the circulating pump, a coupling rigidly connecting the casings of said pumps, said pumps being split in the same vertical plane, and said pumps being offset with respect to the longitudinal vertical center of the condenser, substantially as described.
22. The combination with a surface condenser, of a circulating pump over and upon which the condensate is supported, a condensate pump in line with the circulating pump, a coupling rigidly connecting the casings of said pumps, said pumps being split in the same vertical plane, and said pumps being offset with respect to the longitudinal vertical center of the condenser, together with a pump shaft common to both pumps and removable laterally with its carried pump elements when the split portions of the casings are removed, substantially as described.

In testimony whereof, I have hereunto set my hand.

HAROLD M. GRAHAM.
